UNITED STATES PATENT OFFICE.

GEORGE F. DICKSON, OF CHICAGO, ILLINOIS, ASSIGNOR TO J. G. CHERRY COMPANY, OF CEDAR RAPIDS, IOWA, A CORPORATION OF IOWA.

AIR-COOLING APPARATUS.

1,171,387.

Specification of Letters Patent.

Patented Feb. 8, 1916.

Application filed February 26, 1915. Serial No. 10,713.

To all whom it may concern:

Be it known that I, GEORGE F. DICKSON, a citizen of the United States of America, and a resident of Chicago, in the county 5 of Cook, State of Illinois, have invented certain new and useful Improvements in Air-Cooling Apparatus, of which the following is a specification.

This invention relates to that class of apparatus, in which a flow of air is indirectly cooled by a frigorific mixture of ice and salt or the like. And the present improvement has for its object to provide a simple and efficient structural formation and association 10 of parts, whereby the body of air passing through the apparatus is reduced in temperature in an even, rapid and economical manner, all as will hereinafter more fully appear.

20 In the accompanying drawings: Figure 1, is a side elevation illustrating the preferred form of the present invention. Fig. 2, is a top view with the cover removed. Fig. 3, is an end elevation. Fig. 4, is an enlarged 25 longitudinal section. Fig. 5, is an enlarged transverse section.

Similar reference numerals indicate like parts in the several views.

Referring to the drawings, 1 designates 30 the main casing or housing of the apparatus, preferably of the rectangular box shape shown, and having its side walls, bottom and cover 2, formed with heat insulating linings in any ordinary and usual manner.

35 3 and 4 designate transverse vertical partitions or heads disposed in adjacent spaced relation to the respective end walls of the main casing 1, to divide the same into a central main chamber 5 and a pair of end spaces 40 or conduits, and in the present construction one of said spaces or conduits is sub-divided by a horizontal transverse partition 6 into a lower air inlet chamber 7 and an upper air outlet chamber 8, to which the respective inlet 45 and outlet pipes 10 and 11 are individually connected. With the described arrangement of parts, the other end space or conduit 9 constitutes a return chamber for the passing body of air.

50 12 designates a series of horizontal pipes disposed in vertical and transverse spaced relation in the central chamber 5, aforesaid, and secured at their respective ends to the transverse vertical partitions or heads 3 and 55 4 aforesaid, to provide communication from

the inlet chamber 7 to the return chamber 9, and from said return chamber 9 to the outlet chamber 8 of the apparatus.

13 designates an overflow passage or pipe arranged vertically within the main chamber 5, and passing between the series of horizontal pipes 12 contained in said chamber. The pipe 13 is provided with lateral drain orifices 14 disposed on a plane approximately horizontal with the transverse 60 horizontal partition 6, above described, and as so formed said overflow pipe 13 is adapted to prevent a brine level in the main chamber 5 from rising above the desired level. 70

15 designates a trap connected to the overflow pipe 13 and to a branch pipe 16 having in turn connection with the drain of the building.

17 designates drain pipes having branch 75 connections with the lower portions of the air chambers 7, 8 and 9, and adapted to drain off the water of condensation collected therein during a continued operation of the apparatus. 80

18 designates a power driven air mover, the inlet of which is connected to the outlet chamber 8 of the apparatus by the outlet pipe 11, above described, while the outlet of said air mover 18 has a pipe connection 19 85 extending to the room or place at which it is to supply with cold air. With the described construction the air inlet pipe 10 of the apparatus may connect with the room to which the outlet pipe 19 extends, or to 90 any other suitable source of air supply.

In the practical use of the apparatus, the main chamber 5 is packed with ice in a fragmentary shape and mixed with the requisite quantity of common salt. In continued use 95 a cooled body of liquid brine collects in the lower part of the main chamber 5, and on a level with the horizontal transverse partition 6, so that the lower series of horizontal pipes 12 which receives the initial flow 100 of air, are submerged in said brine and a rapid and effective initial cooling of the air is attained and in view of the rapid heat-interchange which ensues between the cool brine surrounding said pipes and the air 105 passing therethrough.

Having thus fully described my said invention what I claim as new and desire to secure by Letters Patent, is:—

1. In an air cooling apparatus, the com- 110

- bination of a main casing provided with vertical transverse end partitions and a transverse horizontal partition associated with one of said vertical partitions, the said partitions providing a lower inlet chamber an upper outlet chamber and a return chamber, a series of pipes extending horizontally between the vertical partitions aforesaid, and a vertically disposed overflow passage having a drain opening on an approximate level with the horizontal partition aforesaid, the aforesaid transverse horizontal partition being located near the bottom of the apparatus to confine the incoming air to a minor portion of the series of pipes in the initial cooling of the passing air, substantially as set forth.
2. In an air cooling apparatus, the combination of a main casing provided with vertical transverse end partitions and a transverse horizontal partition associated with one of said vertical partitions, the said partitions providing a lower inlet chamber an upper outlet chamber and a return chamber, a series of pipes extending horizontally between the vertical partition aforesaid, a vertically disposed overflow passage having a drain opening on an approximate level with the horizontal partition aforesaid, the aforesaid transverse horizontal partition being located near the bottom of the apparatus

to confine the incoming air to a minor portion of the series of pipes in the initial cooling of the passing air, and a series of drain pipes connecting with the bottom portions 35 of the inlet, outlet and return chambers, aforesaid, substantially as set forth.

3. In an air cooling apparatus, the combination of a main casing provided with vertical transverse end partitions and a transverse horizontal partition associated with one of said vertical partitions, the said partitions providing a lower inlet chamber an upper outlet chamber and a return chamber, a series of pipes extending horizontally between the vertical partitions aforesaid, an air mover connected with the outlet chamber aforesaid, and a vertically disposed overflow passage having a drain opening on an approximate level with the horizontal partition aforesaid, the aforesaid transverse horizontal partition being located near the bottom of the apparatus to confine the incoming air to a minor portion of the series of pipes in the initial cooling of the passing 50 air, substantially as set forth.

Signed at Chicago, Illinois, this 24th day of February, 1915.

GEO. F. DICKSON.
